UNITED STATES PATENT OFFICE.

MARCUS J. DAVIS, OF ST. LOUIS, MISSOURI, ASSIGNOR, BY MESNE ASSIGNMENTS, TO SNAPPY SALES COMPANY, OF WILMINGTON, DELAWARE, A CORPORATION OF DELAWARE.

SUPPORT FOR THE CORDS OF ELECTRIC IRONS.

Application filed November 4, 1922. Serial No. 599,104.

To all whom it may concern:

Be it known that I, MARCUS J. DAVIS, a citizen of the United States, residing at St. Louis, Missouri, have invented a new and useful Support for the Cords of Electric Irons, of which the following is a specification.

This invention relates to a support for the cord of an electric iron.

10 An object of the invention is to provide a device capable of easy attachment to an ironing board or other support for supporting the cord of an electric iron out of contact with the clothes and the ironing board, and 15 possessing the desired characteristics of resiliency and flexibility to permit the iron to be operated easily throughout the length of the board.

Another object of the invention is to provide 20 a device of the character mentioned comprising a coiled spring member and an arm in connection therewith for engaging the cord of an electric iron, and a clamp in connection with the spring member adapted 25 to engage an ironing board or support to hold the device in proper position.

Other objects will appear from the following description, reference being made to the drawing in which

30 Fig. 1 is a plan view showing my invention applied to an ironing board and engaging the cord of the electric iron.

Fig. 2 is a view showing the device in elevation attached to the ironing board.

35 Fig. 3 is an enlarged sectional view of a portion of the spring and the clamp.

In the embodiment of the invention shown the support comprises a coil spring 1 having its upper end extended to provide a relatively long arm 2, the upper end of which is bent to form a socket 3 and a flaring extremity 4 spaced from the arm 2 to leave a space through which the cord of the electric iron is moved into and out of the socket.

40 The lower end of the spring 1 is attached to the upper member 5 of a clamp. The upper clamp member 5 has an ear 6 at each side edge, overlapping the ears 7 on a lower clamp member 8. The two clamp members

are pivotally united by a pin 9 with which 50 the ears 6 and 7 are engaged. A sleeve 10 on the pin 9 strengthens the construction and provides a proper support for the coil spring 11, the ends 12 of which operate to press the inner ends of the clamp member together. 55 The inner end of the upper clamp member has a portion 13 curving downwardly to obtain proper engagement with the ironing board or support to which the device is applied. The lower clamp member 8 is intended to provide a number of pointed projections 14 for the same purpose.

The upper clamp member 5 has a rigid projection 15 which is forced into the end of the spring 1 and which serves to hold the 60 parts together.

In use the device may be applied to the side edge of an ironing board, as shown. The cord 16 of the electric iron is engaged in the socket. The spring 1 and arm 2 have 70 sufficient strength to support the cord and hold it out of contact with the ironing board and the clothes thereon, and they are sufficiently flexible to permit the iron to be operated throughout the length of the ironing 75 board. The spring 1 and the arm 2 bend readily, being resilient so that they spring back to their original upright position as the iron is moved back and forth. The clamp being releasable permits the device 80 to be attached in any desired position along the ironing board and to be removed when the work is finished.

From the foregoing it will be seen that my invention constitutes a highly satisfactory device for preventing the difficulties heretofore experienced on account of the cord of the electric iron getting in the way or contacting with the ironing board or the clothes thereon. The invention may be produced economically and is free from complications.

I do not restrict myself unessentially, but what I claim and desire to secure by Letters Patent is:—

A device of the character described, comprising an upright arm made of a single piece of wire composed of a coil spring por-

tion at its lower end and having the opposite end extending upwardly above the coil spring portion, said coil spring portion being formed by a plurality of superimposed convolutions of the wire and providing a hollow interior, a clamping device for supporting said arm in an upright position,

leaving the spring free to bend and react to its original upright position, said clamp being provided with a projection adapted to be forced into the interior of the coil spring portion constituting a part of the supporting arm.

MARCUS J. DAVIS.
